UNITED STATES PATENT OFFICE

HERMAN E. TROJAHN, OF ST. LOUIS, MISSOURI

COIN-CONTROLLED DRIVE FOR FARE REGISTERS

Application filed April 19, 1927. Serial No. 184,880.

This invention relates to new and useful improvements in fare registers of the type used on busses and street cars. This type of register comprises a comparatively small device capable of being carried in one hand by the busman or conductor and provided at one end with a receiving slot into which the proper coin is inserted by the passenger while the opposite end terminates in a suitable opening through which the coin is ejected after passing through the device. The coin upon being inserted into the slot is gripped by suitable mechanism, which is then automatically operated and causes said coin to traverse said device. During the passage of the coin through the mechanism a suitable registering means is actuated so that accurate record is made of all coins received by the device.

20 The coin receiving and ejecting mechanism is reset after each operation by a plunger arranged so that it may be conveniently operated by the operator.

25 In many instances, particularly on street cars, it is desirable to have the register stationarily mounted so that the fare may be deposited by the passengers as they pass the register.

30 To this end a suitable stand or support is provided for detachably receiving the register, and plunger operating means are arranged in said support for resetting the register after the deposit of each coin.

35 The present practice is to operate said resetting means manually by the operator by means of a handle pivotally mounted on said support. This requires constant attention on the part of the busman or conductor and is impractical as the resetting of the register is dependent upon the manual operation after each insertion of the coin.

40 The present invention has for its object the provision of means for automatically operating the register after each insertion of the coin, thereby relieving the operator from the necessity of manually actuating the register and enabling him to make change, issue transfers, and perform other duties.

45 Other objects of the invention are to provide a motor drive for actuating said regis-

ter and to provide means for effecting the operating connection between said register and said motor drive so that said register shall be operated only at predetermined time relative to the reception of the coin by the register.

50 Further objects of the invention are to provide electro-responsive means for controlling the motor drive of the register resetting means, and to provide an energizing electric circuit for said electro-responsive means, said circuit being controlled by the coin deposited in the register whereby said electro-responsive means are energized and cause the actuation of said register resetting means by said motor drive automatically after each registering operation.

55 Still further objects of the invention are to connect the terminals of the energizing electric circuit of an electro-responsive means to a pair of spaced contacts, insulated from each other and arranged in the path of the coin after the ejection of the latter from the register whereby such coin during its discharge travel engages both of said contacts and completes the circuit of said electro-responsive means so that the latter are energized and effect the operating connection between the register resetting means and a suitable prime mover.

60 Additional objects of the invention are to interpose suitable clutching mechanism between a motor drive and the register resetting means and to provide electro-responsive means controlled by the coin deposited in the register for causing said clutching mechanism to effect the operating connection between said motor drive and said register resetting means.

65 With these and other objects in view, my invention consists in certain novel features of construction and arrangement of parts, hereinafter more fully described and claimed, and illustrated in the accompanying drawings, in which—

70 Figure 1 is a side elevational view of the register support showing parts thereof in cross section and with the register mounted in said support.

75 Figure 2 is a vertical cross section through the device taken at right angles to Figure 1.

Figure 3 is an enlarged sectional detail view taken vertically through the support and showing part of the register in section.

Figure 4 is a sectional detail view taken on line 4-4 of Figure 3.

Figure 5 is a transverse cross section taken on line 5-5 of Figure 3.

Figure 6 is a side elevational view of the clutching mechanism and showing diagrammatically the coin controlled electro-responsive means utilized to control said clutching mechanism.

Figure 7 is a detail view showing the worm drive and the clutching mechanism cooperating therewith.

Figure 8 is a cross section taken longitudinally through the worm gear and the clutching mechanism.

Figure 9 is a fragmental detail view showing the clutching mechanism in driving engagement with the worm gear.

The present invention is illustrated and described as being used in conjunction with the well-known type of fare registers, but it is obvious that other forms of registers or other mechanisms may be reset or operated by my improved coin controlled motor drive.

Referring by numerals to the accompanying drawings, 10 indicates a fare register having one end 11 adapted to receive a coin through a suitable slot formed therein and provided at the opposite end 12 with a downwardly opening pocket 14 into which the coin is ejected by the register. The coin receiving and ejecting mechanism (not shown) is reset after each operation by a plunger 15 which projects outwardly from the register and terminates in an enlargement 16 which is adapted to be manually operated to reset the register mechanism. End 12 is provided with a suitable perforate handle 17 by means of which the register can be conveniently carried by the operator.

When register 10 is stationarily mounted, a stand 18 is provided at a place convenient to the passengers and the operator. This stand comprises a support 19 having parallel vertically disposed side walls 20 connected at their ends by a top wall 21 terminating in a reduced extension 21^a and by a bottom wall 22 having a threaded opening 22^a formed therein. A tubular member 24 is screw-threaded at its upper end into said opening 22^a and at its lower end into an opening 25 formed in a table or shelf 25. A jamb nut 26 is used to lock support 19 against movement on member 24.

A casing 27 serves to enclose support 19 and is provided at one side with an opening 27^a through which the discharge or handle end 12 may be inserted into said casing and into an opening 19^a formed by said walls.

When the register 10 is in position in support 19 the enlargement 16 of plunger 15 is disposed below and in operative rela-

tion with a horizontally disposed roller 28, the ends of which project outwardly through inclined slots 29 formed in said walls 20 and are secured to the upper ends of vertically disposed links 30. The latter are arranged on each side of wall 20 and the lower ends of said links are fixed to the ends of a horizontally disposed rod 31 which extends transversely of support 19 and has its ends projecting outwardly through vertically disposed slots 32 formed in said walls. Engaging rod 31 is the upper end of a connecting rod 34, which latter extends downwardly through tubular member 24 and has its lower end pivotally and eccentrically connected as at 34^a to a disk or cam 35.

This disk is fixed to the projecting end of a shaft 36 which latter is journaled in gear housing 37. This housing is fixed to the underside of table 25 and contains a worm gear 38 which is loosely arranged on shaft 36 and a worm 39 which is in mesh with said gear 38 and is operatively connected by a clutch 40 to an electric motor or other prime mover 41.

The driving connection between worm gear 38 and shaft 36 is effected by a clutching mechanism 42 which is arranged on said shaft and cooperates with the inner annular face 38^a of gear 38. This clutching mechanism includes a spider 44 fixed to the shaft as at 43 and arranged within said gear 38, said spider having radially projecting arms 44^a. A pair of disks 45 and 46 are loosely disposed on each side of said spider and are secured together by a series of pins 47 which extend transversely through the notches 44^b formed by said arms 44^a. Disk 46 which is located exteriorly of gear 38 is provided with a peripheral shoulder 46^a presented in the direction of rotation of gear 38 and adapted to be engaged by a vertically movable stop pin 48 which when in position holds said disks 45 and 46 against rotation. A roller 49 having trunnions 49^a is freely disposed in each notch 44^b and operates between the eccentrically disposed bottom 44^a of each notch and the inner face of the flange of ring 38. Bearing against each roller 49 is a spring-pressed pin 50 which is disposed in each arm 44^a tangentially to the shaft 36 and yieldingly forces said roller toward the high portion of the eccentric bottom.

Disk 46 and spider 44 are yieldingly held in interengagement by a coiled spring 51 connected at one end to a pin 52 of disk 46 and at the opposite end to a pin 54 of spider 44 which pin projects outwardly through a slot 55 formed in disk 46. This spring forms a yielding connection between the conjoined disks 45 and 46, and shaft 36 and spider 44, thereby permitting movement of the respective parts relatively to each other so as to bring rollers 49 into engaging or disengaging positions between said spider and

gear 38. The trunnions 49^a of rollers 49 project into arcuate slots 45^b and 46^b of the respective disks 45 and 46 so that said rollers are restricted in their arcuate movements but are free to move in radial directions.

5 When stop pin 48 occupies interengaged position with shoulder 46^a as shown in Figure 6, spider 44 is so positioned that rollers 49 are disengaged from gear 38. When however, 10 stop pin 48 is moved upwardly out of engagement with shoulder 46^a the conjoined disks 45 and 46 are released against rotation and are moved, under the influence of spring 51, forwardly, thereby bringing rollers 49 against the high portions of eccentric bottoms 15 44^c and interlocking spider 44 with gear 38 so that shaft 36 is set in operation and actuates disk 35. Disk 35 is provided with a shoulder 35^a disposed oppositely with respect to shoulder 46^a of disk 46, and adapted to engage said 20 shoulder 35^a is a pawl 56 which is pivotally arranged on gear housing 37 and is held against disk 35 by a spring 57. Thus when the device reaches home position, pawl 56 25 drops against shoulder 35^a and locks the parts fixed to shaft 36 against rotation in reverse direction. This positions spider 44 slightly forward of disk 46 with pin 54 occupying intermediate position with slot 55 and rollers 30 49 occupying low points of notches 44^b as shown in Figures 6 and 7. Stop pin 48 is operatively carried by one end of a lever 58 which is pivotally mounted at 59 and has its opposite end carrying an armature 60. A 35 spring 58 is connected to lever 58 and has tendency to maintain stop pin 48 against disk 46. Armature 60 cooperates with an electro-responsive means, such as an electromagnet 61, which is adapted to be energized by an 40 electric circuit 62 through a source of electric current 64 arranged in said circuit. This circuit can be manually opened and closed by means of a manually operated switch 65 and the terminals of said circuit are connected to a 45 pair of spaced contacts 66 which are insulated from each other and are contained in a coin discharge passage 67 formed in a chute 68. The latter is formed of insulating material and is disposed in a chamber 69 formed in 50 support 19 and extending in opposite direction from register 10. The upper end of insulating member 68 is provided with a flared-out mouth 67^a which is disposed immediately below a pocket 14 while the discharge end 67^b 55 of said passage 67 opens into a receiving chamber 70 formed in extension 71 by means of a trap door 72. Extension 71 is provided with a window 74 through which the coin deposited in chamber 70 may be observed.

60 The coin upon being ejected from register 10 through pocket 14 drops into the passage 67, where it assumes flat position due to the fact that said passage 67 is formed comparatively shallow and prevents said coin 65 from rolling down said passage edgewise.

Thus said coin is disposed flatwise and in sliding down said passage comes into engagement with both contact members 66, thereby closing the circuit 62 and energizing electro-magnet 61. The energization of electro-magnet 61 70 attracts armature 60 and causes stop pin 48 to be moved upwardly out of engagement with the shouldered portion 46^a of disk 46 so that the latter is allowed to bring the rollers 49 into interlocking engagement with gear 75 38 and spider 44, thereby setting in operation the resetting means and restoring the register in readiness for the next coin registering operation.

In order to prevent too rapid discharge of 80 the coin through the passage 67 and the consequent opening of the circuit before stop pin 48 has been moved into released position, a gate 75 is arranged in support 19 and slidably extends transversely into passage 67 so as to arrest the coin in its travel and cause it to come to rest while in engagement with contacts 66. This gate which is preferably formed of insulating material so as not to affect the contacts 66 extends 85 into the interior formed by walls 20 and has a slot and pin connection with one end of a bell crank 76 which is pivotally mounted at 77 and has its other end operatively connected with connecting rod 34. Thus as soon 90 as the resetting means is set in operation by the closing of circuit 62 and connecting rod 34 is moved downwardly, bell crank 76 is operated, causing gate 75 to be retracted from passage 67, thereby releasing the coin 95 100 so that the latter can continue in its travel through passage 67 and be discharged into compartment 70. Trap door 72 is adapted to be actuated through suitable means 78 by the lower end of one of the links 30 so that said door is opened and the coin deposited in the lower chamber 70^a from which the coins may be removed in opening spring-pressed door 79.

The roller 28 is so disposed that register 110 10 may be readily moved into and out of position in support 19. As the driving connection is not effected until after the coin has been ejected from the register, all danger of injury to the register, caused by the 115 forcible operation of the plunger when the registering mechanism is locked, is thereby eliminated and if the register mechanism is locked the coin will be retained in the register and the resetting means cannot be operated. The clutch 40 provides safety means for releasing the motor from the resetting means in case the latter is rendered inoperative.

120 My improved coin control drive is of simple construction, can be readily attached to existing forms of registers, and supports for same, and is entirely automatic in operation so that no attention on the part of the operator is required.

While I have described the device for use with coins, it will be readily understood that metallic fares, such as tokens now widely used on street cars, can be equally as well used without necessitating any structural changes in the device.

The electrical control herein described and illustrated can be used for actuating various other forms of registering devices. The electric motor 41, which in the present instance is used as the prime actuator, is preferably operated continuously while the register is used and only the clutching mechanism is controlled by the electric circuit. This eliminates wear and tear on the motor due to frequent starting and insures quick operation. Any suitable source of electrical current can be used in connection with the energizing circuit; it may be supplied either by batteries or by the trolley line of the street cars.

While I have shown and described the preferred form of my invention, it is obvious that various changes in the construction and arrangement of the parts can be made and substituted for those herein shown and described, without departing from the spirit of my invention.

I claim:

1. A coin controlled fare registering device comprising in combination with a register, means for resetting the same, a prime mover for said resetting means, a clutching mechanism interposed between said resetting means and said prime mover, means for normally disengaging said clutching mechanism, an electro-responsive means for actuating, when energized, said disengaging means to release said clutching means, an electric circuit for energizing said electro-responsive means, a pair of spaced terminal contacts interposed in said circuit, said contacts being insulated from each other and adapted to be interconnected by a coin discharged by said register to cause the completion of said circuit, whereby said register is operated by said actuating means upon discharge of said coin.

2. A coin controlled fare registering device comprising in combination with a register, a chute for receiving the fare discharged by said register, means for resetting said register after the discharge of coin therefrom, a prime mover for said resetting means, a clutching mechanism interposed between said resetting means and said prime mover, means for automatically disconnecting said clutching mechanism after each cycle of operation, an electro-responsive means for placing said disconnecting means and releasing said clutching mechanism, an electric circuit for controlling said electro-responsive means, a pair of spaced terminal contacts interposed in said circuit and located in said chute in the path of the discharged fare,

said contacts being insulated from each other and adapted to be interconnected by said fare to complete said circuit, and a member disposed in said chute and movable in correlation with said resetting means into and out of the path of said fare for temporarily arresting the movement thereof while in engagement with said terminal contacts.

3. A coin controlled driving mechanism comprising a chute for receiving a coin, and actuating shaft, a prime mover for driving said shaft, a clutching mechanism for interengaging said prime mover with said shaft, said clutching mechanism including a driving element in positive engagement with said prime mover, a driven element fixed to said shaft, and means for interengaging said elements and normally spring-held in disengaged position, a displaceable member in engagement with said element engaging means, a spring connected to said member for bringing said means into element engaging positions; a stop member for engaging said displaceable member and locking the latter against the influence of said spring, an electro-responsive means for moving said stop member out of engagement with said displaceable member whereby said clutching mechanism is rendered operative, an energizing electric circuit for said electro-responsive means, a pair of spaced terminal contacts arranged in insulated relation in said chute and disposed in the path of a coin deposited therein, whereby said circuit is completed by the interengagement of said coin with said contacts and said driving mechanism is rendered active, and a member arranged in said chute in the path of said coin for temporarily arresting the movement thereof while in engagement with said terminal contacts and movable to release said coin after the energization of said electro-responsive means.

4. A coin controlled driving mechanism for fare registering devices comprising in combination with register resetting means and driving means for said resetting means, of a chute for receiving a fare after its ejection from the register, a clutching mechanism interposed between said resetting means and said driving means, a stop member for disengaging said clutch mechanism, electro-responsive means for operating said stop member to release said clutch mechanism, an energizing electric circuit for said electro-responsive means, and a pair of contacts in said chute and insulated from each other and interposed in said circuit for normally maintaining said circuit open, said contacts being adapted to be engaged by the metallic fare deposited in said chute, thereby closing said circuit and energizing said electro-responsive means.

5. A coin controlled driving mechanism for fare registering devices comprising in

- combination with a fare register, register resetting means, and driving means for said resetting means, of a chute for receiving a fare after its ejection from said register, a clutching mechanism interposed between said resetting means and said driving means, a stop member for disengaging said clutching mechanism, electro-responsive means for operating said stop member, an energizing electric circuit for said electro-responsive means, a pair of spaced contacts disposed in said chute and insulated from each other, said contacts being interposed in said circuit for normally maintaining said circuit open, and being adapted to be engaged by a metallic fare during its passage through said chute, thereby closing said circuit and energizing said electro-responsive means, and a member movable within said chute into the path of said metallic fare for temporarily arresting the movement thereof while in engagement with said contacts. 6. In a metallic fare registering device, the combination with a registering mechanism having a resetting plunger, of means for actuating said plunger, driving means for said actuating means, a clutching mechanism interposed between said actuating means and said driving means and including a revolute member provided with a radially disposed shoulder, a stop member cooperating with said revolute member and adapted to engage the shoulder thereof for rendering said clutching means inoperative, a spring for maintaining said stop member in engagement with said revolute member, electro-responsive means for moving said stop member out of engagement with said revolute member, thereby rendering said clutching mechanism effective, an energizing electric circuit for said electro-responsive means, and a pair of terminal contacts arranged in said circuit, said contacts being insulated from each other and adapted to be engaged and complete said circuit by a metallic fare passing over said contacts. 7. A coin controlled device for fare registering devices comprising in combination with register resetting means and driving means for said resetting means, of a clutching mechanism interposed between said resetting means and said driving means, a member for disengaging said clutch mechanism, electro-responsive means for operating said disengaging member, an energizing electric circuit for said electro-responsive means, a pair of contacts insulated from each other and interposed in said circuit for normally maintaining said circuit open, said contacts being adapted to be engaged by a metallic fare after its ejection from said registering device, thereby closing said circuit and energizing said electro-responsive means, a member movable into the path of said metallic fare for temporarily arresting the movement thereof while in engagement with said contacts, means for actuating said fare arresting member, and a spring for bringing said disengaging member into engagement with said clutching means to disengage the operative connection between said driving means and said resetting means. 8. In a metallic fare registering device, the combination with a registering mechanism, of means for resetting the same, driving means for said resetting means, a clutching mechanism interposed between said resetting means and said driving means, a stop member cooperating with said clutching means for disengaging the operative connection between said driving means and said resetting means, an operating member for actuating said stop member, electro-responsive means actuating said operating member for moving said stop member out of engagement with said clutching means, an energizing electric circuit for said electro-responsive means, a pair of terminal contacts arranged in said circuit, said contacts being insulated from each other and adapted to be engaged and complete said circuit by a metallic fare passing over said contacts, and a gate member movable upwardly above the top plates of said contacts for arresting said metallic fare while in engagement with said contacts. 9. In a metallic fare registering device, the combination with a registering mechanism, of means for resetting the same, driving means for said resetting means, a clutching mechanism interposed between said resetting means and said driving means, a stop member cooperating with said clutching means for controlling the operative connection between said driving means and said resetting means, an operating member for actuating said stop member, electro-responsive means actuating said operating member for moving said stop member out of engagement with said clutching means, an energizing electric circuit for said electro-responsive means, a pair of terminal contacts arranged in said circuit, said contacts being insulated from each other and adapted to be engaged and complete said circuit by a metallic fare passing over said contacts, a gate member movable upwardly transversely of said contacts into the path of travel of said metallic fare for temporarily retaining the latter in electrical contact with said contacts, and a lever operable by said resetting means for actuating said gate member. 10. In a fare registering device, the combination with a fare register having a resetting plunger, of means for actuating said plunger and including a pair of reciprocable spaced bars and a rod extending between the upper ends of said bars and engaging said plunger, a revolute shaft, and a link operatively connecting one end of said shaft with the lower ends of said bars; driving

means for operating said shaft, a clutching mechanism interposed in said driving means for controlling the operative engagement between said driving means and said shaft, a stop member cooperating with said clutching mechanism for normally maintaining said shaft and said actuating means inoperative, electro-responsive means for moving said stop member out of engagement with said clutching means, thereby effecting operative connection between said driving means and said shaft of said actuating means, and an energizing circuit for said electro-responsive means, said circuit being normally opened and adapted to be closed by a coin which it is desired to register.

11. In a fare registering device, the combination with a fare register having a resetting plunger, of means for actuating said plunger and including a pair of reciprocable spaced bars and a rod extending between the upper ends of said bars and bearing against said plunger, a revolute shaft, and a link operatively connecting one end of said shaft with the lower ends of said bars; a coin receiving chute having an upper end disposed in correlation with the coin discharge end of said register, driving means for operating said shaft, a clutching mechanism interposed in said driving means for controlling the operative engagement between said driving means and said shaft, a stop member cooperating with said clutching mechanism for normally maintaining said shaft and said actuating means inoperative, electro-responsive means for moving said stop member out of engagement with said clutching means, thereby causing operative connection between said driving means and said shaft, an energizing circuit for said electro-responsive means, said circuit being normally opened and adapted to be closed by a coin which is discharged from said register into said chute, and means for bringing said stop member into engagement with said clutching means for interrupting the operative connection between said driving means and said actuating means.

12. A coin controlled driving mechanism for coin registers comprising a register resetting mechanism, an actuator for said mechanism, clutching means for normally disengaging said actuator from said mechanism, said means including a pair of clutch elements, means for interengaging said elements, and a spring actuating member for bringing said means into element interengaging positions; a pawl adapted to engage said spring actuated member so as to lock it against the spring influence and hold said means in disengaged positions, electro-responsive means for moving said pawl out of engagement with said spring actuated member, thereby rendering said clutching means operative and effecting interengagement

means for actuating said member, driving mechanism for said actuating means and including a clutch mechanism and a stop member cooperating with said clutch mechanism and normally occupying a position for rendering said clutch mechanism inoperative; electro-responsive means for displacing said stop member so as to release said clutch mechanism, a circuit for energizing said electro-responsive means and including a pair of spaced terminal contacts; means for conveying the coin discharged from said register over said contacts to complete said circuit so as to release said clutch mechanism and render said device operative for resetting said register, and means operable in conjunction with said actuating means for temporarily retaining said coin in engagement with said contacts, said retaining means being operable to release said coin during the operation of said actuating means.

16. In a coin registering device, the combination with a coin register adapted to receive and register a coin and then discharge it, of a support for supporting said register, a member reciprocably mounted in said support for resetting said register, a revolute shaft, a connecting link operatively associated with one end of said shaft for actuating said reciprocable member, driving means for actuating said shaft, said driving means including a clutch, a stop member cooperating with said clutch for normally holding said clutch in disengaged position, electro-responsive means for displacing said stop member so as to render said clutch operative and complete the driving connection between said driving means and said reciprocable member, a circuit for energizing said electro-responsive means, a coin chute disposed in said support and having one end arranged adjacent to the discharge end of said register to receive the coin discharged thereby, a pair of spaced contacts arranged in said chute forming the terminals of said circuits whereby the coin during its passage through said chute completes said circuit, thereby energizing said electro-responsive means and rendering said clutch operative for resetting said coin register.

In testimony whereof I hereunto affix my signature this 14th day of April, 1927.

HERMAN E. TROJAHN.
